UNITED STATES PATENT OFFICE.

EDWARD E. FRANCE, OF RACINE, WISCONSIN.

TOY.

Application filed January 21, 1925. Serial No. 3,857.

To all whom it may concern:

Be it known that I, EDWARD E. FRANCE, a citizen of the United States, residing at Racine, in the county of Racine and State 5 of Wisconsin, have invented new and useful Improvements in Toys, of which the following is a specification.

This invention relates to a toy, the general object of the invention being to provide 10 means whereby marbles or the like can be caused to travel from one end of the rotary member to the other and then returned to their starting point through the body of the member.

15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views and in which:—

Figure 1 is a side view of the invention.

Figure 2 is an end view thereof.

Figure 3 is a section on line 3—3 of 30 Figure 2.

Figure 4 is a fragmentary end view.

In these views, 1 indicates a cylindrical member of slightly tapered shape with a bore 2 at its center, the ends of the bore 35 being plugged by the hub pieces 3. A spiral groove 4 is formed in the exterior of the member and a hole 5 connects one end of this spiral groove with the bore 2. A hole 6 is formed adjacent the other end of the member 40 and communicates with the bore and this bore is connected by the zigzag groove 7 with the other end of the spiral groove. A frame 8, preferably formed of wire, and of inverted U-shape, has its limbs formed with 45 bearings for the hub pieces 3 so that the member 1 is rotatably mounted in the frame. A handle 9 is connected with one of the hub pieces so that the member can be rotated. The bight of the frame forms a pair of track 50 members 10 spaced above the top of the member 1 with one track member bent to form an extension 11 which will act as a guard for the front end of the spiral groove 4 as will hereinafter appear. A strip of 55 wire bent to form a pair of track members 12, is fastened to the front or large end of

the member 1, and is arranged to receive a marble 13 or other sphere passing through the hole 6 and to support the same when that portion of the member 1 carrying the track members 12 is lowermost.

From the foregoing it will be seen that when a marble is dropped through one of the holes into the bore 2 of the member 1, and the member rotated in a clockwise direction the marble will pass through the hole 6, when this part of the member 1 is moved downwardly beyond a horizontal position, and will roll upon the track member 12 which will support it. As the track members 12 move upwardly the marble will be supported by the rear ends of such members until the part of the member 1 carrying the zigzag groove 7 approaches its highest point when the marble will roll into the angle part 7' of the groove 7 which slopes towards the spiral groove so that the marble will pass down this part 7' into the spiral groove. As will be seen, the ball is carried up by the track members 12 until it nears the top of 75 the device, when it will roll down the groove 7', as this groove slopes, due to the tapered formation of the body 1. At this point the end of the spiral groove will be under the guard 11 so that this guard will catch the 80 marble and prevent it from rolling off the member 1. Then during the continued rotation of the member 1 the track members 10 will cause the marble to remain at the top of the member 1 and it will thus follow the 85 groove until it reaches the end of the groove and drops into the hole 5. The marble will then roll down the bore 2 and pass through the hole 6 again and thus the operation will 90 be repeated again and again as long as the member 1 is revolved. Of course a number of marbles or other spheres can be used, as shown in Figure 1. This device will afford 95 amusement to children and other persons.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a supporting frame, a member rotatably mounted therein and having a bore and a spiral groove on its exterior with passages 110

- connecting the ends of the grooves with the bore, means permitting the member to be rotated, a spherical member, means for holding the spherical member at the top of the 5 rotatable member and to cause it to engage the spiral groove as the member is rotated and means for catching the spherical member as it leaves one of the holes and directing it into the spiral groove.
- 10 2. A device of the class described comprising a frame, a cylindrical member of slightly tapered shape rotatably mounted in the frame, said member having a spiral groove therein and holes connecting the ends of the 15 groove with the bore of the member, track members formed with the frame at the top thereof for causing a spherical member to engage the spiral groove, bars connected with the large end of the cylindrical member for catching the spherical member as 20 it drops through the hole at this end of the cylindrical member and directing it into the end of the spiral groove and a guard on the
- frame for preventing the spherical member from rolling off the cylindrical member. 25
3. A device of the class described comprising a supporting frame of inverted U-shape, a horizontally arranged rotary member supported by said frame, said rotary member being of cylindrical shape and slightly tapered and having a bore at its center, a cylindrical groove on its exterior and a hole connecting one end of the groove with the bore, a Z-shaped groove connected with the other end of the spiral groove and a hole connecting the zigzag groove with the bore, the bight of the frame forming track means, a pair of track members carried by the rotary member and arranged adjacent the second hole in the rotary member and a spherical member adapted to travel along the 30 grooves and the holes and bore of the member when the same is rotated. 35
- 40 In testimony whereof I affix my signature.

EDWARD E. FRANCE.
